UNITED STATES PATENT OFFICE.

FLORIMUNDO CABRAL, OF FALL RIVER, MASSACHUSETTS.

CLOTHES PRESS.

Application filed February 15, 1927. Serial No. 168,436.

Devices, containers or stretchers for garments are known to the prior art and many devices have been proposed for maintaining garments, such as trousers and coats in a pressed condition, however, none of these devices have gone into extensive use.

It is an object of my invention to provide a clothes press simple in design and reliable in operation for holding coats and trousers in a pressed condition.

Another object of my invention is to provide a clothes press on the order of a very shallow suitcase wherein the trousers are disposed within the interior of one half and the coat and vest within the interior of the other half, each half having spring-urged strips on each side thereof that press against the creased portions of the garments contained therein.

Other objects and advantages will appear from the following detailed description.

I attain these objects and advantages by means of the mechanism illustrated in the accompanying drawing wherein:

Figure 1 is a view in perspective showing the clothes press in its opened condition with the coat and trousers shown pressed down by the spring-urged pressing members.

Figure 2 is an elevational view showing the clothes press in its closed condition having the appearance of a suitcase.

Referring to the drawings, the clothes press there illustrated comprises the receptacle members A, B, which are hinged together to form a box. They are of sufficient width to accommodate either a coat or trousers in the same position as when the coat is hung on a coat hanger and the trousers suspending their entire length. The width of the members A, B, is governed by the width of the coat R in the position shown in Fig. 1 and the length determined by the length of the trousers S. The depth of each member is shallow being sufficient only to accommodate the garments. It should be understood however, that these suggested dimensions may be varied to accommodate additional garments.

Each of the members consists of a bottom member C, sides D, and ends E; and they are hinged at F so that they close together. Within the interior of each member at the sides D thereof, are disposed pressing members G. The pressing members are narrow strips of metal, wood or other suitable material in parallel relation to the sides and of

sufficient width and length to cover the creased portions in the garments. The pressing members are secured to the interior of the members A, B, by spring hinges H 60 whereby the pressing members G are forced against the bottoms of the members A, B. The spring hinges H are secured to the members A, B, through the medium of the narrow holding strip members J to which the spring 65 hinges are attached, the strip members J being secured to the bottom or sides of the interior of the box-like members A, B. Fastening means L and handle means K are provided for respectively locking the box-like 70 members together and to render the same easily portable.

The manner and use of the hereinbefore described invention is as follows. The clothes press is opened to the position shown 75 in Figure 1. The garments such as the coat or trousers are disposed and folded in to the position in which the creased portions form the edges of the garments, such as shown by the dotted lines in Figure 1 (this is what I 80 term the "stretched out" condition). The pressing members are raised and the coat or trousers lowered into place, care being taken to preserve the creased portions at the edges, and the pressing members released. It will 85 be appreciated that the force of the pressing members will maintain and preserve the creases in the garments. The amount of pressure exerted by the pressing members may be varied by using a stronger or weaker 90 spring hinge.

The section which contains the coat will generally provide enough unused space (see Figure 1) to accommodate a vanity box or loose articles.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure which utilize the principle of my invention and fall within the 100 purview of my invention and are within the spirit and scope of the following claim.

The invention having been set forth, what is claimed as new and useful is:

A clothes press for holding garments in a 110 stretched out condition, comprising a shallow hinged receptacle member, said receptacle

member having spring-urged pressing means on the sides thereof, said pressing means comprising long narrow anchoring strips adjacent the sides of said receptacle member, 5 pressing members, spring hinges, said pressing members being attached to said anchoring strips by means of said spring hinges,

said pressing members being flared upwardly at their opposing edges.

Signed at Fall River in the county of 10 Bristol, State of Massachusetts, this eleventh day of February, 1927.

FLORIMUNDO CABRAL.
